W. L. BESSOLO

WRENCH

Filed July 9, 1923

UNITED STATES PATENT OFFICE.

WILLIAM L. BESSOLO, OF CLEARWATER, CALIFORNIA.

WRENCH.

Application filed July 9, 1923. Serial No. 650,274.

This invention has to do with a wrench adapted to handle pipes, tubings, etc., and it is an object of the invention to provide a simple, effective, improved tool of this general character.

It is an object of this invention to provide an improved and practical means for automatically releasably connecting the outer end of the flexible jaw of a wrench with the operating lever upon the jaw being arranged in operating position around the pipe, or the like.

It is another object of this invention to provide a wrench construction in which the mechanism carried by the lever for releasably connecting the flexible jaw with the lever is protected so that it cannot become broken or damaged with ordinary use of the tool.

Another object of this invention is to provide means for connecting the outer end of the flexible jaw with the lever so that force applied through the lever is transmitted to the outer end of the jaw in a direct and particularly effective manner and without passing through a pivotal connection.

The various objects and features of my invention will be best and more fully understood from the following detailed description of a typical preferred form of the invention, throughout which description reference is had to the accompanying drawings, in which:

Fig. 1 is a view showing my improved wrench in operating position on a pipe;

Fig. 2 is a view similar to Fig. 1, showing the wrench with a side plate removed, and showing the wrench released ready to be removed from the pipe, and

Fig. 3 is an enlarged detail sectional view, taken as indicated by the line 3—3 on Fig. 1.

My improved wrench includes, generally, a lever 10, a flexible jaw 11, means 12 permanently connecting the inner end of the flexible jaw 11 with the lever, and means 13 for releasably connecting the outer end of the jaw with the lever.

The lever 10, in accordance with my invention, is preferably a unitary member, for instance, a forging, having a handle 14, and a head 15 at the inner end of the handle 14. The head 15 is flat, and is, in accordance with the preferred form of construction, somewhat offset to one side with relation to the longitudinal axis of the handle 14.

The flexible jaw 11, which I have illustrated in the drawings, is in the form of a chain including a plurality of links 16 connected by pintle pins 17. In accordance 60 with the broader aspects of my present invention, the jaw 11 may be constructed in various manners, so long as it has the desired flexibility, and gripping action.

The means 12 provided for connecting the inner end of the flexible jaw 11 with the head 15 of the lever 10, includes cheek or side plates 18, a pivot pin 19 connecting the inner end of the jaw with the side plates, and a pivot pin 20 connecting the side plates 70 with the head 15. The side plates 18 are arranged at opposite sides of the head 15, and are pivotally connected with the head 15 by the pin 20 so that they have parts 21 projecting outwardly from the head. The link 75 16, at the inner end of the flexible jaw 11, is arranged between the projecting parts 21, and is connected with the projecting parts by the pivot pin 19.

The means 13 includes, generally, an arcuate jaw 22 pivotally connected with the outer end of the flexible jaw 11 by a pivot pin 23, and a catch 24 carried by the head 15 to cooperate with the jaw 22. The jaw 22 is preferably an arcuate jaw, and is provided 80 at its outer edge with ratchet teeth 24^a, having flat faces 25 facing inwardly or toward the flexible jaw 11. The catch 24 is in the form of a block having teeth 26 on its outer side. The catch 24 is arranged at the outer 90

part of the head 15 so that its teeth 26 will cooperate with the teeth 24^a of the jaw 22 upon the jaw being arranged in operating position between the pipe "P" and the head 15, substantially as I have illustrated in Figs. 95 1 and 2 of the drawings. In accordance with my present invention the catch 24 is mounted on a stem 27 slidably carried in an opening 28 formed through the head 15 substantially parallel to the longitudinal axis 100 of the handle 14. The stem 27 projects outwardly from the outer part of the head 15 and carries the catch 24 so that it is spaced from the outer part of the head. A helical spring 29 is carried on the stem 27 between 105 the catch 24 and head 15 so that it normally yieldingly holds the catch 24 out or away from the head 15. The inner end of the stem 27 projects from the inner part of the head 15 at the side of the handle 14 and carries an operating handle or knob 30. The knob engages the head to limit the outward 110

movement of the stem and catch and is adapted to be operated to withdraw the catch from its out position. It is to be noted that the handle 30 is in a convenient position for operation and that it does not project or protrude in a manner to be unsightly or in any way inconvenient.

In accordance with my present invention the head 15 has a part 32 which extends or projects outwardly from the main part of the head beside the catch 24 so that the catch has sliding engagement with it and so that it operates to support or back up the catch to relieve the stem 27 when the tool is operated, as hereinafter described. The part 32 is preferably made comparatively heavy so that it is strong and rigid. Further, in accordance with my present invention, I make the side plates 18 comparatively wide opposite or at the means 13 so that they completely cover and protect the catch part 24, and form a housing or guide for the jaw 22 at the catch 24.

I provide a gripping plate or jaw 40 between the projecting parts 21 of the side plates 18. The jaw 40 has a lug part 41 that is carried by the pivot pin 19. The edge or side portions of the jaw 40 are supported in seats or recesses 43, provided in the projecting parts 21, so that the face 44 of the jaw is in position to engage and grip the pipe when the tool is operated. The jaw 40 is more fully described and is claimed in my copending application entitled Tools, filed 35 August 13, 1923, Serial No. 657,024.

From the foregoing description it will be apparent that the spring 29 normally holds the catch 24 out in the position shown in Fig. 1. To apply the wrench the flexible jaw 11 is arranged around the pipe "P", or other object to be operated, and the jaw 22 is arranged between the said plates 18 and between the pipe "P" and catch 24. As the jaw 22 is arranged in position the teeth 24^a pass over the teeth 26 and, as the parts approach the position where they are tight, the catch 24 is depressed to allow the teeth 24^a to pass the teeth 26. When the parts are in the position illustrated in Fig. 1 the tool is in position ready for operation. To operate the tool so that it grips and turns the pipe "P" the handle 14 is swung in the direction indicated by the arrow "A" in Fig. 1, so that the head 15 turns relative to the plates 18 in the direction indicated by the arrow "B" in Fig. 1, thereby causing the catch 24, which has gripping engagement with the jaw 22 through the teeth 26 and 24^a, to move or urge the jaw 22 toward the inner end of the flexible jaw 11. When the flexible jaw has been made tight on the pipe further movement of the handle 14 will cause turning of the pipe. When it is desired to release the tool the handle 30 is operated so that the catch 24 is withdrawn from the jaw 22, al-

lowing the jaw to be withdrawn from position between the catch 24 and pipe and the flexible jaw 11 to be freely opened.

Having described only a typical preferred form of my invention I do not wish to limit myself to the specific details hereinabove set forth but wish to reserve to myself any changes or variations that may appear to those skilled in the art or fall within the scope of the following claims.

Having described my invention, I claim:

1. A wrench including, a lever including a handle and a head at one end of the handle, a flexible jaw having one end secured to the lever, and means for releasably operatively connecting the other end of the jaw with the lever including, a stem slidably carried by the head so that it is substantially parallel with the handle of the lever, a catch member fixed on the outer end of the stem, a spring arranged between the catch member and head to normally yieldingly hold the catch member in position to directly cooperatively engage the jaw, and an operating handle for the stem mounted on the inner end of the stem.

2. A wrench including, a lever including a handle and a head at one end of the handle, a flexible jaw having one end secured to the lever, and means for releasably operatively connecting the other end of the jaw with the lever including, a stem slidably carried by the head so that it is substantially parallel with the handle of the lever, a catch member fixed on the outer end of the stem, a spring arranged between the catch member and head to normally yieldingly hold the catch member in position to directly cooperatively engage the jaw, and a part on the inner end of the stem to cooperate with the head to limit the movement of the catch member by the spring and forming an operating handle for the stem.

3. A wrench including, a lever including a handle and a head at one end of the handle, the head having an opening through it substantially parallel with the handle, a flexible jaw having one end secured to the lever, and means for releasably operatively connecting the other end of the handle with the lever including, a stem slidably carried in said opening, a catch member fixed on the stem at the outer part of the head, a spring carried on the stem between the head and said member to normally yieldingly hold the member out to directly cooperatively engage the jaw, and an operating handle mounted on the inner end of the stem.

4. A wrench including, a lever including a handle and a head at one end of the handle, the head having an opening through it substantially parallel with the handle, a flexible jaw having one end secured to the lever, means for releasably operatively connecting the other end of the handle with the

lever including, a stem slidably carried in said opening, a catch member fixed on the stem at the outer part of the head, a spring carried on the stem between the head and 5 said member to normally yieldingly hold the member out to directly cooperatively engage the jaw, and an operating handle mounted on the inner end of the stem at the handle of the lever, and a projection on 10 the head directly engaging the catch member to brace it.

5. A wrench including, a lever having a handle and a head at the inner end of the handle, the head having a part extending 15 from one side beyond the handle and having an opening through said part substantially parallel with the handle, a chain having one end pivotally connected with the head, a jaw on the other end of the chain, the jaw having teeth at its outer edge, a stem slidably carried in said opening, a catch member fixed on the stem at the outer part of the head and adapted to cooperate with the teeth of the jaw to releasably operatively 20 connect the jaw with the head, a spring on the stem between the head and said member to normally yieldingly hold the member out in position to directly cooperate with the teeth, a handle on the inner end of the stem 25 30 at the handle of the lever, and a part pro-

jecting outwardly from the head at the side of said member to directly engage and brace said member.

6. A wrench including, a lever, a flexible jaw having one end secured to the lever, and means for releasably operatively connecting the other end of the jaw with the lever embodying, a stem slidably carried by the lever, a catch member fixed on the stem, means normally yieldingly holding the catch member in position to directly co-operatively engage the jaw, and a handle connected with the stem for operating the stem to move the catch member out of said position.

7. A wrench including, a lever including a handle and a head at one end of the handle, a flexible jaw having one end secured to the lever, and means for releasably operatively connecting the other end of the jaw with the lever including, a stem, a catch member fixed on the stem, means normally yieldingly holding the catch member in position to directly cooperatively engage the jaw, and an operating handle for the stem located at the handle of the lever.

In witness that I claim the foregoing I have hereunto subscribed my name this 29th day of June, 1923.

WILLIAM L. BESSOLO.
